INVENTOR
Dearly A. Smith
BY *Arthur G. Brown*

ATTORNEY

UNITED STATES PATENT OFFICE.

DEARCY A. SMITH, OF KANSAS CITY, MISSOURI, ASSIGNOR TO THE ASKEW SADDLERY CO., OF KANSAS CITY, MISSOURI, A CORPORATION OF MISSOURI.

HORSE-COLLAR NECK PAD.

Application filed December 5, 1927. Serial No. 237,778.

My invention relates to horse collars and particularly to neck pads for collars of this class, the principal objects of the invention being to provide a neck pad having a smooth under surface, to provide a pad adapted for collars of different sizes, to insure the proper positioning of a neck pad on the neck of a horse, and to support a pad securely in functioning position.

10 In accomplishing this and other objects of my invention, I have provided improved details of structure, the preferred forms of which are illustrated in the accompanying drawings, wherein:

15 Fig. 1 is a perspective view of the parts embodying my invention attached to a collar.

Fig. 2 is a cross section on the line 2—2, Fig. 3.

Fig. 3 is a section on the line 3—3, Fig. 2.

20 Fig. 4 is a detail perspective view of the neck pad, disassembled from the collar.

Referring more in detail to the drawings:

1 designates a horse collar having ends 2 and 3, held together in adjustably spaced relation by a billet 4 provided with a buckle 5.

In usual practice a neck pad is secured near its center to one of the adjoining ends of the collar. However, this method does not insure that the center of the pad will rest on the center of the horse's neck since the position of the pad will be shifted more or less to one side or the other of the central position in proportion to the variations in space between the adjoining ends of the collar caused by obvious necessary adjustment.

To overcome this and other objectionable features of ordinary pad means I provide a shaped pad 6 preferably formed of leather, having upstanding front and rear arcuate flanges 7 and 8 and a metal body plate 9 having complementary depending flanges 10 and 11 secured to the pad by suitable means such as rivets 12. The plate 9 is further provided with spaced elongated openings 13, and with a post 14 positioned between the openings for purposes later to be described. A curved raised portion 15 near the forward end of the metal plate is provided for additional space at that point between the plate and pad to receive the bead portion 16 of the collar, and also to provide for proper positioning of the upper hame strap of harness. The flanges 7 and 8 of the pad are further supported, near

their outer ends by straps 17 and 17' secured thereto as by rivets 18.

55 In assembling my invention with a collar of ordinary construction, the end of the collar to which the billet is fastened is passed between the strap 16 and the pad. The billet is then inserted from beneath through the first of 60 the elongated openings of the plate, passed over the post, and then inserted from above through the remaining opening. The desired position of the pad in relation to the collar, in view of desired spacing of the ends of 65 the collar, is conferred by selecting the proper hole in the billet to engage the post on the bridge plate. The other end of the collar is then passed between the strap 17 and the pad and adjustably secured by the billet and 70 buckle in the usual manner.

The pad may, therefore, be applied to a collar requiring for effective use my desired spacing of the ends of the collar, the ends of the collar sliding over equal portions of the pad to 75 center the pad on the collar, and the bridge plate attached to the pad providing means enabling the collar-attached billet to latch the pad in centered position.

What I claim and desire to secure by Letters 80 Patent is:

1. In combination with a collar having abutting ends, a billet carried by the collar, a pad for underlying the ends of the collar, a plate secured to and spaced from the pad to receive the ends of the collar therebetween, and means on the plate for adjustably anchoring the billet.

2. In combination with a collar having abutting ends, a pad for underlying the ends 90 and a billet carried by the collar, a plate secured to and spaced from the pad to receive the ends of the collar therebetween, and a post on the plate for adjustably anchoring billet.

3. A neck pad including a pad body, a support fixed to and spaced from said body having spaced transverse slots, and a post on the support between the slots, the post being constructed and arranged to anchor a billet 100 passed through the slots.

4. In combination with a collar having free ends, a pad underlying the free ends of the collar, a plate fixed to and spaced from the pad having transverse, spaced slots, a billet on the collar threaded through said slots and 105

means on the plate between the slots for anchoring the billet.

5. In combination with a collar having separate ends, a pad underlying the ends of the collar, a plate fixed to and spaced from the pad, having spaced, transverse slots, a post on the plate between the slots, and a billet on the collar extended through said slots, having openings adapted for selectively receiving the post to adjustably anchor the billet.
10. In combination with a collar, a pad hav-

ing upstanding flanges at its longitudinal edges, a plate having downturned end flanges secured to the pad flanges and spacing the plate from the pad, and having slots arranged transversely of the pad, a post on the plate between the slots, and a billet on the collar threaded through said slots and anchored to said post. 15

In testimony whereof I affix my signature.

DEARCY A. SMITH.
